UNITED STATES PATENT OFFICE.

CHARLES F. ECKHART, OF MILWAUKEE, WISCONSIN.

LIGHTING FIXTURE

1,405,674.

Specification of Letters Patent. Patented Feb. 7, 1922.

Application filed February 7, 1921. Serial No. 443,138.

To all whom it may concern:

Be it known that I, CHARLES F. ECKHART, a citizen of the United States, and resident of Milwaukee, in the county of Milwaukee and State of Wisconsin, have invented new and useful Improvements in Lighting Fixtures, of which the following is a description, reference being had to the accompanying drawings, which are a part of this specification.

This invention relates to certain new and useful improvements in lighting fixtures and refers more particularly to that type of fixture, the base or body of which is preferably formed of molded plastic material.

It is the present custom in manufacturing lamps in which the body is formed of molded material to provide an expensive form of lamp socket, which materially increases the cost of production thereof.

Hence with the above and other objections in mind my invention has for one of its objects to provide an improved method for molding the lamp stand in which the lamp receiving socket is constructed in the cheapest manner possible, and secured in place at the time of molding the base.

Another object of this invention is to provide a lamp fixture of the class described in which the light receiving socket is molded at the time of forming the fixture, and is surrounded by a boss or projection to which a shade support may be readily attached.

A further object of this invention resides in the novel method of molding the fixture whereby the electric cord attaching plug is utilized to retain the socket forming means in position while the fixture is being molded.

A still further object of this invention is to provide a light fixture of the class described, which may be made in various designs such as that of the Kewpie doll, Lily doll or in any other desired form.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention con-

structed according to the best mode I have so far devised for the practical application of the principles thereof, and in which:

Figure 1 is a front elevational view of a lamp fixture, embodying my invention, the lamp base or support proper being molded in the form of a Lily doll;

Figure 2 is a fragmentary top plan view, looking at the lamp receiving socket on the plane of line 2-2 of Figure 3; and

Fig. 3 is a section on line 3-3 of Fig. 2.

Figure 4 is a fragmentary view, taken through the head end of the improved form of mold I employ in constructing lighting fixtures embodying my invention, said view being part in section and part in elevation.

Referring now more particularly to the accompanying drawing in which like numerals designate like parts throughout the several views:

The numeral 5 designates generally the body portion or supporting base of my new, improved device, which in the present instance is the form of a doll having the improved form of lamp receiving socket, hereinafter described, in which is removably secured an electric light globe 6.

The body 5 is formed of plastic material, which is poured in a two part mold 7, which has the end walls thereof, forming the head 8 recessed or counter bored as at 9, and provided with an opening 10 communicating with said recess and adapted to have a terminal plug 11 projected therethrough into the interior of the mold. The plug 11 is of conventional construction and, prior to its insertion in the mold, has an internally and externally threaded metal sleeve 12, preferably of copper, screwed thereon to lie within that portion of the mold defined by recess 9.

Prior to the final insertion of the plug 11, with the sleeve 12, into the mold, one end of a wire 13 has the insulation removed therefrom and secured to the sleeve 12 by twisting the same therearound as at 14 and a wire 15 has the insulation removed from one end which is secured to the plug 11 by the usual center terminal screw 16 thereof. In securing the end of wire 15 by the screw 16, said screw is only partly driven home and the wires 13 and 15 are then strung centrally through the mold as illustrated in Figure 4.

After the mold has thus been set, the material is poured therein and when sufficiently hardened the plug 11 is unscrewed. By

- reason of the screw 16 being but loosely secured in place, the same will be readily unscrewed from the plug 11 and when it is completely removed from the mold, leaving the 5 sleeve 12 in place, the screw 16 is disengaged from the end of the wire 15, thus leaving the bared end 17 for engagement with the central terminal 18 of the globe 6, the other side terminal of which contacts with the socket 12.
- 10 The finished article has a projection or boss 19 formed thereon by the recess 9 in the mold which boss provides ready means of attachment for a support 20 for a suitable shade 21. Support 20 has a lower split ring 15 22, which engages about the boss 19, and is finally clamped or secured thereto by the binding means 23.
- From the foregoing description taken in connection with the accompanying drawing 20 it will be readily apparent that I provide a lighting fixture in which the lamp receiving socket is formed in an inexpensive manner and at the same time gives the desired results and produces a fixture of ornamental 25 and pleasing appearance.

What I claim as my invention is:

1. As an article of manufacture, a lighting fixture molded of plastic non-conducting material, an internally and externally

threaded open ended metallic sleeve set in 30 the fixture at its time of molding to provide an electric lamp receiving socket, an electric feed wire having one end twisted about the exterior of said sleeve to have an electrical connection therewith, and a second electric 35 supply wire having one end projected into the space within said sleeve to provide a contact for one terminal of the lamp, the other terminal of said lamp contacting with said sleeve.

2. As an article of manufacture, a lighting fixture moulded of plastic non-conducting material, an open ended internally threaded metal bushing set in the fixture at 40 its time of moulding to form a lamp receiving socket, an electric wire electrically connected with said sleeve prior to the moulding of the fixture, and a second electric wire having its end terminating in said socket, said second wire being set in place prior to the 45 moulding of the fixture and insulated from the other wire by the material forming the fixture, the bushing forming one terminal for a lamp secured in the socket and the end of the second wire forming a terminal for 50 the lamp.

In testimony whereof, I affix my signature,
CHARLES F. ECKHART.
